UNITED STATES PATENT OFFICE

GUSTAV BUTZKE, OF SCHENECTADY, NEW YORK, ASSIGNOR TO GENERAL ELECTRIC COMPANY, A CORPORATION OF NEW YORK

ADAPTER FOR VACUUM-TUBE SOCKETS

Application filed June 5, 1923. Serial No. 643,593.

The present invention relates to the wireless communication art, and more especially to the means for mechanically supporting and electrically connecting in circuit the vacuum tubes commonly known as radiotrons.

The sockets or receptacles for the standard radiotrons are made with a base receiving recess of about one and three-eighths inches in diameter and with the filament contacts arranged at two adjacent corners of a rectangle and the grid and plate contacts at the other two corners. The miniature radiotrons, which have come into recent extensive use, have a base about one inch in diameter and with the plate and grid contacts transposed or arranged diagonally thereon and accordingly is incapable of being directly mounted in standard radiotron sockets or receptacles.

The object of the present invention is to provide a hardy, compact and easily applied adapter whereby a miniature vacuum tube may be readily and properly connected to a standard radiotron socket or receptacle.

One embodiment of the invention is shown in the accompanying drawing in which Fig. 1 is a top plan view of my adapter; Fig. 2 is a vertical sectional view of the outer shell on line 2-2 of Fig. 1 with the base plate and contacts shown in position in side elevation; Fig. 3 is a disassembled perspective view with the shell in part section, and Fig. 4 is a disassembled perspective view of the contacts and the interior base plate.

The supporting member comprises a shell 1 made of insulating compound in the form of a cup with a peripheral flange 2 knurled at its edge 3 to provide a good hand hold. The exterior size and shape thereof correspond with those of the base of the standard vacuum tube. It has a radial positioning and holding spur 4 secured in its cylindrical outer wall for engagement with the bayonet slot of the socket and four countersunk apertures 5 symmetrically disposed in the bottom part 6 for the passage therethrough of the external contact fingers 7.

The base plate 8, forming the inner part of the support, is made of insulating compound in the form of a disk adapted to fit the recess of the shell 1. It has a peripheral notch 9

adapted to receive a feather lug 10 formed on the inner wall of the shell near the bottom thereof and serving angularly to position the base plate therein. The base plate 8 and the bottom 6 of the shell have axial holes 11 and 12 for the passage of an assembly screw 13 which is adapted to engage a nut 14 carried by the base plate.

The contact fingers 7 have shouldered projections 15, while their inner ends are threaded for engagement with nuts 16 set in the upper side of the plate about the holes 17 formed therein for the passage of the finger contacts. Rectangular recesses 18 are formed in the lower side of the base plate 8 about the holes 17 for the reception of similarly shaped ends 19 of the opposite or internal contact springs which are secured therein by the shoulders 15 of the contact fingers 7 bearing thereagainst when screwed home.

The four opposite spring contacts 20, 21, 22 and 23 are shaped differently from one another due to the transposed or dissimilar arrangement of the contacts on the standard and the miniature vacuum tubes. Contact 20 has its free tip disposed axially above its contact finger 7 and is accordingly bent into the form of a letter U. Contact 21 has its tip disposed diametrically opposite its contact finger 7 and is made in the form of a long lever. Contact 22 has its tip disposed over the contact finger 7 ninety degrees in advance. Contact 23 is similar to contact 22 and all contacts have intermediate shank portions 24 adapted to enter peripheral notches 25 in the base plate and to be braced by the side walls thereof while the outer portions of the spring contacts overlie freely the outer side of the base plate. The tip portions 26 of the spring contacts are made oblong to provide somewhat extended areas upon which the contact fingers 27 (indicated in dotted circles in Fig. 1 of the miniature vacuum tube may slide during the angular movement thereof as it is connected to and disconnected from the adapter. This connection is the usual bayonet joint consisting of a radial spur on the tube similar to spur 4 and an L-shaped slot 28 formed in the inner wall of the shell 1, as shown in Fig. 3.

When the adapter is inserted in a standard vacuum tube socket, the spur 4 and its co-operating bayonet slot definitely position the contact fingers 7 so that the left-hand pair, as shown in Fig. 3, may engage the filament terminals while the upper right-hand finger engages the grid terminal and the remaining finger engages the plate terminal. Similarly when a miniature vacuum tube is inserted in the adapter, its filament terminals engage spring contacts 21 and 23, its grid terminal engages spring contact 22 and its plate terminal the contact 20.

While I have shown and described the best embodiment of the invention known to me, I do not desire to be restricted thereto.

What I claim as new and desire to secure by Letters Patent of the United States, is,—

1. A tube socket adapter comprising a cylindrical shell of insulation having external means for attaching and positioning within a tube socket and internal means for attaching and positioning a tube of reduced diameter therein, a set of external contacts carried by said shell and adapted to engage socket contacts, and a set of internal contacts directly connected to said external contacts with their free ends arranged in transposed relation to the external contacts and adapted to engage tube contacts.

2. A tube socket adapter comprising a shell of insulation provided with means for positioning and attaching within a tube socket and for positioning and attaching a tube of reduced diameter therein, an insulating base mounted in fixed position within said shell, a set of external contacts mounted on one side of said base and adapted to engage socket contacts, and a set of internal contacts mounted on said external contacts and projecting from the opposite side of said base in transposed relation to the first set of contacts and adapted to engage tube contacts.

3. A tube socket adapter comprising a cylindrical shell of insulation having external means for attaching and positioning within a tube socket and internal means for attaching and positioning a tube therein, an insulating base fixedly positioned within said shell, a set of external contacts mounted on and projecting from the rear side of said base, and a set of internal contacts connected to said external contacts and their free ends extending over the front side thereof with the order of arrangement differing from that of the external contacts.

4. A tube socket adapter comprising an insulating disk base having a set of peripheral notches, a set of socket engaging contacts mounted on and projecting from the rear side of said base, a set of leaf spring contacts respectively connected to said socket engaging contacts at the rear side of said base and their free ends extending through the respective peripheral notches therein and dis-

posed over the front side thereof with their order of arrangement differing from that of the socket engaging contacts.

In witness whereof, I have hereunto set my hand this 4th day of June, 1928.

GUSTAV BUTZKE.
